WRITING INSTRUMENT

Raymond A. Lanoie, East Greenwich, R.I., assignor to Lew Mfg. Co., Coventry, R.I., a corporation of Rhode Island

Filed Apr. 21, 1969, Ser. No. 16,837

Term of patent 14 years

Int. Cl. D19—06

U.S. Cl. D74—17

FIG. 1

FIG. 2

FIG. 3

FIG. 4

FIG. 1 is a perspective view of a writing instrument showing my new design;

FIG. 2 is a top plan view thereof;

FIG. 3 is a fragmentary side elevational view thereof, on an enlarged scale; and

FIG. 4 is a section taken on line 4—4 of FIG. 3.

The essential features of my design reside in the outward flared top portion which is faceted around and which faceted portion is enclosed at the top and bottom by an annular contrasting band, similar contrast being applied to the top end; all as shown.

I claim:

The ornamental design for a writing instrument, substantially as shown and described.
